UNITED STATES PATENT OFFICE

115,244

DESIGN FOR AN ELECTRIC WATER PUMP UNIT

Milford L. Williams, Moline, Ill.

Application February 7, 1939, Serial No. 82,824

Term of patent 7 years

To all whom it may concern:

Be it known that I, Milford L. Williams, a citizen of the United States, residing at Moline, in the county of Rock Island and State of Illinois, have invented a new, original, and ornamental Design for an Electric Water Pump Unit, of which the following is a specification, reference being made to the drawing, forming a part thereof.

In the drawing:

Fig. 1 is a top perspective; and

Fig. 2 is a bottom perspective view of an electric water pump unit showing my new design.

I claim:

The ornamental design for an electric water pump unit, as shown.

MILFORD L. WILLIAMS.
